(57) **ABSTRACT**

The reciprocating engine comprises a rocker valve gear, pistons which are fastened to a connecting rod and connected by crankshaft journals to a crankshaft, a balancer, and a camshaft which is driven by the crankshaft and in turn actuates rockers, the mentioned elements being arranged in a crankcase having a cylinder head and cylinder head cover. The cylinder head is provided with integrally cast or screwed-on receivers serving for the attachment of the hollow camshaft without requiring separately fastened bearing blocks. Correspondingly, the cylinder-head comprises further integrally cast or screwed-on receivers which serve for the attachment of the hollow rockers without requiring separately fastened bearing blocks.

RECIPROCATING ENGINE WITH ROCKER
VALVE GEAR

This application is a division of Ser. No. 09/762,784 filed Feb. 12, 2001 now U.S. Pat. No. 6,520,133, which is a 371 of PCT/EP99/05714 filed Aug. 6, 1999.

The present invention describes a reciprocating engine with rocker valve gear according to the preamble of the independent claims. By way of example, the invention will be explained in more detail with reference to a 2-cylinder in-line engine, but it applies to reciprocating engines having any desired number of cylinders.

Engines having different kinds of valve gears are known in the art, e.g. according to FIG. 1, which schematically shows four different valve gears as described in the book *Kraftfahrtechnisches Taschenbuch Bosch*, published by VDI-Verlag, 19th edition, for example. One possible embodiment is the rocker valve gear shown in FIG. 1, drawing 3. Today, this kind of valve gear is used especially in engines where low friction and a low construction height are primary requirements. The drawbacks of this design are substantially greater complications in machining and assembly of the valve gear, costly maintenance, and an increased space consumption in the longitudinal direction of the cylinders.

U.S. Pat. No. 5,605,077 discloses a reciprocating engine where the diameter of the bearings receiving the camshaft increases in the mounting direction, so as to facilitate the insertion of the camshaft. However, the precise machining of these bearing holes with different diameters is very costly. The reference also discloses that the rockers are supported at the same bearing locations, the bearings being enlarged at the locations of the rocker bores. Due to the fact that the rocker bores are disposed in the cylinder block, the assembly of the rockers can only take place in the cylinder head.

On the background of this prior art, it is the object of the present invention to eliminate the drawbacks of anterior rocker valve gears with respect to substantially greater complications in machining and assembly of the camshaft and of the rockers, costly maintenance, and increased space consumption in the longitudinal direction of the cylinders. An engine with rocker valve gear of this kind is defined in the independent claims. Further advantages and embodiments are described in the dependent claims.

The invention is described in more detail hereinafter with reference to a drawing of solutions of the prior art and with reference to an exemplary embodiment of a 2-cylinder in-line engine.

FIG. 1 schematically shows four possible valve gears;

FIG. 2 schematically shows a lateral view of a valve gear of an engine of the invention;

FIG. 3 shows a sectional view according to line III—III in FIG. 2;

FIG. 4 shows the rocker arrangement of FIGS. 2 and 3 in a top view;

FIG. 5 shows a top view of the crankshaft and the balancer of FIG. 2;

FIG. 6 schematically shows a first cross-section of the cylinder head enclosure of the invention;

FIG. 7 shows another cross-section of the cylinder head enclosure of the invention; and

FIG. 8 shows a perspective view of a variant of the embodiment of FIG. 7.

FIGS. 2 to 5 schematically show parts of the driving mechanism of a reciprocating engine of the invention, with pistons 1, of which only one is shown, and which are fastened to connecting rods 2 and connected by crankshaft

2

journals 3 to crankshaft 4. Further shown are a balancer 5 comprising chain wheel 5K, a chain wheel 6 which is directly connected to the crankshaft, as well as a chain tensioning wheel 7 which drives the camshaft chain wheel 9, thus allowing camshaft 10 to be rotated and to actuate rockers 11, which move the schematically indicated valves 19 along valve axis 12.

An internal combustion engine of the reciprocating type as represented in the exemplary embodiment by a so-called 10 in-line engine comprises two parallel, non-represented cylinders in which the pistons 1 and 2 reciprocate. The crankshaft 4 arranged below the cylinders comprises two crankshaft journals 3 on each of which a respective connecting rod 2 is journaled. Each one of the connecting rods is connected 15 to a piston 1 reciprocating in the respective cylinder. A camshaft 10 is arranged on top of the cylinders. The cams 18 of camshaft 10 actuate rockers 11 which cooperate with the corresponding valves 19.

Camshaft 10 is driven by a camshaft chain wheel 9 which 20 is arranged between the pairs of cams for the individual cylinders. In the exemplary embodiment, this camshaft chain wheel is disposed in the center of the camshaft, but in other embodiments, it might be offset from the center.

Camshaft 10 is driven by crankshaft 4 through control 25 chain 8 via camshaft chain wheel 9, chain tensioning wheel 7, counter-rotating balancer 5 with balancer chain wheel 5K, and crankshaft chain wheel 6. Another possible embodiment of the camshaft driving mechanism comprises a toothed belt and toothed wheels instead of a chain and chain wheels.

The sectional views of FIGS. 6 and 7 illustrate the 30 assembly of camshaft 10 and of rockers 11 directly into integrally cast receivers 15 and 16 of cylinder head 24. This offers the advantage of a very simple machining and a very simple assembly of the camshaft and the rockers. FIGS. 6 and 7 only show portions of cylinder head 24 and cylinder head cover 14, in which all the described elements are 35 arranged.

The assembly will be explained and the advantages will 40 be pointed out in more detail herebelow with reference to camshaft 10. According to the present invention, the integrally cast receivers 16 in cylinder head 24 for camshaft 10, which is a hollow shaft, only need to be bored to the desired shaft dimension, such that camshaft 10 provided with internal roller bearings 20 can be placed between receivers 16, 45 and camshaft axle 17, which serves as a mounting shaft, can be pushed in. Cylinder head cover 14 with correspondingly machined lateral surfaces 21 serves for laterally maintaining camshaft axle 17.

Correspondingly, this also applies to rockers 11, which 50 are also in the form of hollow shafts with roller bearings 22, and which are placed according to FIG. 7 between receivers 15, whereupon rocker axles 13, which serve as mounting shafts, are pushed in and are maintained by lateral surfaces 23 of cylinder head cover 14.

Thus, one advantage of the invention is a very simple 55 machining of the valve gear and a very simple assembly of the camshaft and of the rockers. Another advantage of the invention is the use of roller bearings for the camshaft and the rockers, whereby very low friction losses are possible and no pressure lubrication is necessary.

Another important advantage of the invention is that no 60 additional fastening of bearing blocks by screws or by other means is necessary. Due to the special design of the cylinder head cover, the latter needs no bearings. Furthermore, there are no interrupted sealing surfaces between the cylinder head cover and the cylinder head, and a very simple sealing of the spark plug bore is possible. Due to the possibility of

3

using the cylinder head cover for the fastening of axles 13 and 17, no further securing of the camshaft and of the rockers is necessary. The invention also allows a significant simplification of servicing operations such as valve clearance control and adjustment, and the camshaft and rockers are extremely easy to replace.

FIG. 8 shows a design variant of the receivers, more particularly of the rocker shaft receivers, the cylinder head being illustrated in a perspective view. It has been found that cast receivers for the rocker shafts fail to meet the requirements of certain models and under high stresses. In such cases, in the embodiment of FIG. 8, the cast receivers 15 according to FIG. 7 may be replaced by steel receivers 15A which are directly screwed to cylinder head 24 in pairs. The other advantages of the cast receivers are entirely conserved, and the assembly of the rocker shafts is effected in the same way.

If necessary, the cast camshaft receivers 16 may also be replaced by prefabricated receivers which are subsequently screwed to the cylinder head.

Furthermore, it has been found that the use of receivers, either of cast receivers or of prefabricated and screwed ones, offers substantial advantages and economies also for the mounting of camshafts or rockers of the prior art. In analogy, it has been found that the use of hollow shafts for the mounting of camshafts and rockers offers advantages also in arrangements of the prior art.

Especially in FIG. 3, it appears that camshaft 10, chain tensioning wheel 7, and counter-rotating balancer 5 with chain wheel 5K are driven by crankshaft 4 through a single chain 8 arranged in line with the crankshaft and its chain wheel 6. This offers the advantage that the very compact design allows a very slim construction, and that additional components such as intermediate shafts may be omitted. Also, due to the location of chain tensioning wheel 7, this arrangement of the chain allows a reversed direction of rotation of balancer 5 and a sufficient angle of contact of all driving and driven components. Chain tensioning wheel 7 is arranged in line with crankshaft chain wheel 6 in such a manner that both a sufficient angle of contact for all shafts

4

and a reversed direction of rotation of balancer 5 are obtained. For reduced friction, chain tensioning wheel 7 may comprise roller bearings while being sufficiently lubricated by splash oil of the chain.

This feature of the invention also contributes to a very simple and compact design of the valve gear. Instead of a chain drive, the invention may be embodied with toothed belts. In this case, the chain wheels will be replaced by toothed belt wheels.

What is claimed is:

1. A reciprocating engine comprising:

at least one cylinder having a piston therein, the piston being coupled by a connecting rod and crankshaft journals to a crankshaft; a camshaft which is driven by the crankshaft; and a rocker mechanism driven by the camshaft, all of which are arranged in a crankcase having a cylinder head and cylinder head cover;

wherein the camshaft is comprised of a hollow member having internally disposed bearings by which the camshaft is mounted for rotation on a stationary internal axle.

2. A reciprocating engine according to claim 1, wherein the internal camshaft bearings are roller or plain bearings.

3. A reciprocating engine according to claim 1, further including receivers which are cast integrally with the cylinder head and which support the internal axle on which the camshaft rotates.

4. A reciprocating engine according to claim 1, further including receivers which are prefabricated from steel and screwed to the cylinder head and which support the internal axle on which the camshaft rotates.

5. A reciprocating engine according to claim 1, wherein the cylinder head cover includes lateral surfaces which serve for positioning and laterally maintaining the position of the camshaft and the associated camshaft axle.
